UNITED STATES PATENT OFFICE.

ALEXANDER MILNE, OF NEWARK, NEW JERSEY, ASSIGNEE TO NEWARK WATCH CASE MATERIALS COMPANY, OF NEWARK, NEW JERSEY, A CORPORATION OF NEW JERSEY.

WATCH-HOLDER.

1,202,561.

Specification of Letters Patent. Patented Oct. 24, 1916.

Application filed March 9, 1916. Serial No. 33,022.

To all whom it may concern:

Be it known that I, ALEXANDER MILNE, a citizen of the United States, and a resident of Newark, in the county of Essex and State 5 of New Jersey, have made and invented certain new and useful Improvements in Watch-Holders, of which the following is a specification.

My invention relates to a holder for 10 watches, which, although particularly designed and constructed so as to support a watch in a conspicuous position upon the dashboard of an automobile, may also be used in other and varied places, such as upon 15 the post of a bed, or as a desk stand.

An object of the present invention is to provide a holder for a watch which may be stamped or drawn from sheet metal, allowing it to be easily and economically manu- 20 factured, and of such style and arrangement that the completed article will possess a neat and pleasing appearance, and accordingly add to the attractiveness of the dashboard of an automobile, with its complement of 25 switches and accessory instruments.

A further object is to provide a holder which is adapted to receive and support an open-face watch, of the popular and inexpensive type, such as manufactured by Robert H. Ingersoll & Bro., and so display the watch as to form an efficient substitute for the more expensive types of dashboard 30 clocks.

The holder is so constructed that after the 35 time-keeping qualities of the watch have become impaired, a new watch may be easily and quickly inserted in place.

A further object is to provide a holder for a watch wherein the crown is spaced a distance from the supporting surface, so that the winding of the watch may be conveniently accomplished.

With the foregoing and other objects in view, which will appear as the description 45 proceeds, my invention resides in the combination and arrangement of parts and in the details of construction hereinafter described and claimed.

The preferred embodiment of my invention 50 is disclosed in the accompanying drawings, wherein:—

Figure 1 is a view in perspective of the watch holder, embodying the characteristic features of my invention, the bezel-engaging ring being illustrated in its open position; Fig. 2 is a view in central vertical section of the watch holder, with a watch positioned therein; Fig. 3 is an enlarged view in front elevation of the upper rear portion of the holder, illustrating the locking arrangement 60 for securing the bezel-engaging ring in its closed position; Fig. 4 is a fragmental view in vertical section taken on the line 4—4 of Fig. 3; Fig. 5 is a view in vertical section taken on the line 5—5 of Fig. 3; Figs. 6 and 65 7 illustrate several uses to which the watch holder may be put; Fig. 8 is a view in front elevation of a somewhat modified form of watch holder; and Fig. 9 is a view in vertical section taken on the line 9—9 of Fig. 8. 70

Referring specifically to the several views, the body of the watch holder is stamped from a single piece of sheet metal and comprises the outer annular and apertured flange 15, from the inner periphery of which projects an annular and inclined wall 16 which is in the form of a truncated pyramid. The outer extremity of this inclined and annular wall is inwardly depressed and curved toward the plane of the flange, 80 though offset therefrom, and forms the back plate 17 of the watch receptacle. The back plate 17 is curved and so shaped as to correspond to the curvature of the rear wall of the particular type of watch the holder 85 is to contain. Hingedly secured to the inclined wall 16, is the bezel-engaging ring 18, which extends over the bezel 19 of the watch and forms, in connection with the back plate 17, a housing or receptacle 20 in which a 90 watch is contained. The pendant of the watch projects through suitable and registering notches 21, formed in the bezel-engaging ring and the inclined wall 16.

The bezel-engaging ring is provided with 95 a tongue 22 which projects through an opening 23 formed in the inclined wall of the holder when the bezel-engaging ring is in its closed position. A latch 24 is carried by the inclined wall of the housing, and is 100 adapted to be turned into engagement with the tongue of the bezel-engaging ring, and

lock the ring in its closed position. The latch member includes a small trunzion 25, projecting through the inclined wall of the holder, and so shaped as to be engaged by a key for the locking or releasement of the front wall of the watch-containing receptacle.

The holder as thus constructed, is particularly adapted for supporting the less expensive classes of watches in some readily discernible position upon an automobile, the rear plate and bezel-engaging member being provided with a lining 26, preventing the scratching of the case of the watch and absorbing the larger part of vibrations and jars to which the watch will be necessarily exposed when in use upon the automobile. The watch holder is, however, capable of varied and extensive uses; for instance, it may be used in connection with a hinge 27, disclosed in Fig. 6, and mounted upon the post of a bed, whereby it may be moved so as to be plainly visible, or may be folded against the post, and so occupy an unobtrusive position.

A further use which the holder may serve is illustrated in Fig. 7, in which instance a pair of hinged legs 28 are secured to the upper extremity of the flange of the holder, and allow the device to occupy a position upon a desk or other flat surface, and so act as a desk clock.

The modified form of holder disclosed in Figs. 8 and 9, is constructed from a single piece of metal, stamped or drawn so as to form a flange 30, from which projects an outwardly shaped open cup-like receptacle 31, through the upper wall of which extends the opening 32, for the reception of the pendant of a watch which the holder is to contain and support. The upper portion 33 of the flange is concave, and is approximately tangential at its central point to the upper extremity of the cup-like receptacle 31.

31. A spacer 34, approximating the outline of the flange 30, is secured to the rear of the flange and maintains the entire device spaced a distance from the surface upon which it is supported. The concavity of the upper extremity of the spacer and flange allows the winding of the watch to be conveniently accomplished. A lining 37 is also provided in this type of holder, and protects the watch to a certain extent against jars and vibrations.

What I claim is:—

1. A watch holder comprising a flat flange or plate, a substantially circular wall carried thereby and projecting therein front, a back plate connected to the outermost extremity of said wall and curved to correspond to the rear surface of a watch, and a front wall provided with a central opening connected to the outer extremity of the said

substantially circular wall and forming, in connection with said back plate, a watch receptacle, said front wall curved to correspond to the front portion of a watch.

2. A watch holder comprising a flange with a central portion thereof outwardly extended and forming a curved back plate adapted to receive the rear of a watch thereagainst, a bezel-engaging ring hinged to said back plate and locking means adapted to hold said bezel-engaging ring to said back plate.

3. A watch holder comprising an annular flange, an inclined wall carried thereby, and a back plate carried by said inclined wall, a bezel-engaging ring carried by said inclined wall and forming in connection with said back plate a watch-receiving receptacle.

4. A watch holder comprising a flange with the central portion thereof outwardly extended and forming a back plate adapted to receive the rear of a watch thereagainst and maintain the same in front of the plane of said flange, a bezel-engaging ring hinged to said back plate and forming in combination therewith a watch-receiving receptacle, and locking means adapted to hold said bezel-engaging ring in spaced relation with said back plate.

5. A watch holder comprising an annular flange, an inclined wall carried at the inner periphery thereof, a back plate carried by said inclined wall and offset therefrom, and lying between the plane of the flange and plane of the outer extremity of said inclined wall, a bezel-engaging ring carried by said inclined wall and adapted to secure a watch against said back plate.

6. A watch holder comprising an annular flange, an inclined wall carried at the inner periphery thereof, a back plate carried by said inclined wall and offset therefrom, and lying between the plane of the flange and plane of the outer extremity of said inclined wall, a bezel-engaging ring carried by said inclined wall and adapted to secure a watch against said back plate, and inter-engaging means carried by said inclined wall and said bezel-engaging member, locking the two against displacement.

7. A watch holder comprising an annular flange, an inclined wall carried at the inner periphery thereof, a back plate carried by said inclined wall and offset therefrom, and lying between the plane of the flange and plane of the outer extremity of said inclined wall, a bezel-engaging ring carried by said inclined wall and adapted to secure a watch against said back plate, said inclined wall and bezel-engaging ring provided with aligned notches for the reception of the pendant of a watch thereon.

8. A watch holder comprising an annular flat flange with openings therein for the

passage of securing means therethrough, a wall carried by said flange and projecting thereinfront, a bezel-engaging ring carried by said wall, and means for holding a watch against said bezel-engaging ring and housed within said wall.

Signed at New York, borough of Manhat-

tan, in the county of New York and State of New York, this 8th day of March, A. D. 1916.

ALEXANDER MILNE.
